UNITED STATES PATENT OFFICE.

SAMUEL DUVALL, OF CHICAGO, ILLINOIS.

PULVERIZING MILL.

Application filed June 20, 1928. Serial No. 286,790.

This invention relates to new and useful improvements in mills, and particularly to pulverizing mills.

One object of the invention is to provide a device of this character, and of the rotary beater type, wherein the beaters are so arranged that the pulverizing action, upon the material, is more efficient, and wherein such material is properly acted upon by all of the hammers of the beater.

Another object is to provide a rotary beater wherein the hammers are arranged in groups, and such groups arranged in staggered relation to the adjacent groups, where by the hammers of one group attack the material, and then such material is attacked by the next adjacent staggered group.

Another object is to provide a novel and efficient means, arranged between the sets of hammer groups, which are arranged to move the material toward one group, and then toward the other group, with the result that the material is properly pulverized to the desired degree.

Other objects and advantages will be apparent from the following description when taken in connection with the accompanying drawing.

In the drawing:

Figure 1 is a vertical transverse sectional view, through a mill made in accordance with the present invention.

Figure 2 is a vertical longitudinal central sectional view, on the line 2—2 of Figure 1.

Figure 3 is a detail view showing the material propellers 27 and 28.

Referring particularly to the accompanying drawings, 10 represents a cylindrical casing, which is properly supported on the legs 11, and having a feed opening 12 in one side, and a hinged cover 13, on its upper side. Extending longitudinally within the casing, and having its ends journaled in the end walls of the casing, is a shaft 14. Fixed on the end portions of the shaft, within the casing, are the disks or plates 15 and 16, respectively, and, fixed on the intermediate portion of the shaft is a disk or plate 17. The disks or plates 15 and 16 are formed with the radial arms 18, each having an opening 19 in its outer end. In the central disk 17, in alinement, respectively with the openings of the end plates, are openings 20. It will be particularly noted that the openings 20, of the disk 17, which aline with the openings 19, of the disk or plate 15, are stag-

gered with relation to the openings which aline with those of the other plate 16. Secured within the openings 20 of the disk 17, and extending toward the opposite ends of the casing, in alternate succession, are the rods or shafts 21 and 22, the former having their other ends secured within the openings of the plate 15, while the latter have their other ends secured within the openings of the plate 16. Loosely mounted on the rods or shafts 21 are the radially extending arms or hammers 23, while similar arms or hammers 24 are mounted on the rods or shafts 22. Suitable spacing washers 25 are disposed between the hammers 23, on the rods or shafts 21, while similar spacing washers 26 are disposed on the rods or shafts 22, between the hammers 24. Secured to the central disk 17, and extending radially therefrom, at two diametrically opposite points, are the material propeller arms 27 and 28, the former of which has its outer end slightly curved transversely, and twisted out of the plane of the remainder or body portion thereof, while the latter has its outer end similarly formed, but twisted in the opposite direction to that of the first arm. These arms are arranged to successively engage the material operated upon by the hammer arms, to move such material toward one end of the casing, to be acted upon by the hammers 23, in one instance, and toward the other end of the casing, to be acted upon by the hammers 24, in the second instance, with the result that such material will be in constant motion, longitudinally of the casing, to be thoroughly pulverized.

The bottom of the casing is removed, and removably secured therein is a downwardly bowed, longitudinally extending screen 29, through which the pulverized material passes, after being properly acted upon by the hammers 23 and 24.

One end of the shaft 14 is provided with a pulley 30, to receive power from any suitable source, for rotating the shaft, whereby to cause the hammers to act upon the material.

In the drawings a feed hopper 31 is removably connected in the feed opening, but it will be understood that a feed table may be readily substituted therefor, in accordance with the conditions, or the desire of the user.

Removably secured to the inner faces of the casing and the cover thereof, are the lining sections 31, which are preferably formed

from metal, and serve to protect the casing from damage by the material being ground.

What is claimed is:

1. A pulverizing mill including a casing and a shaft mounted therein, staggered groups of hammers mounted on the shaft, and radially extending arms arranged to force the material alternately toward the opposite ends of the casing for crushing action by the staggered groups of hammers.
2. A pulverizing mill including a casing

and a shaft mounted therein, staggered groups of hammers mounted on the shaft, and a plurality of radially extending oppositely twisted arms disposed between the groups of hammers for successively and alternately propelling the material from one end of the casing to the other end thereof for alternate and successive action by the hammer groups.

In testimony whereof, I affix my signature.

SAMUEL DUVALL.
